UNITED STATES PATENT OFFICE.

WILL S. JAMES, OF TEHUACANA, TEXAS.

SASH-FASTENER.

SPECIFICATION forming part of Letters Patent No. 643,356, dated February 13, 1900.

Application filed July 29, 1899. Serial No. 725,527. (No model.)

To all whom it may concern:

Be it known that I, WILL S. JAMES, a citizen of the United States, residing at Tehuacana, in the county of Limestone and State of Texas, have invented a new and useful Sash-Fastener, of which the following is a specification.

The invention relates to improvements in sash-fasteners.

The objects of the present invention are to improve the construction of sash-fasteners, to lessen the cost of construction, and to provide a simple, inexpensive, and efficient device capable of holding a sash at any desired adjustment and of being arranged to lock the sashes against vertical movement on each other.

Another object of the invention is to provide a device of this character which may be arranged to permit a sash to be raised to the desired extent and hold the same at the desired adjustment and which may also be held in a retracted position to permit a sash to move freely in either direction.

Furthermore, the invention has for its object to enable the casing and the bolt to be cast and readily assembled and to arrange the parts so that they will be retained in position when the device is secured to a sash.

The invention consists in the construction and novel combination and arrangement of parts hereinafter fully described, illustrated in the accompanying drawings, and pointed out in the claims hereto appended.

In the drawings, Figure 1 is a perspective view of a portion of a window provided with a sash-fastener constructed in accordance with this invention. Fig. 2 is a vertical sectional view of the same, the bolt being arranged to present an upper beveled face. Fig. 3 is a similar view, the spring-actuated bolt being arranged to present upper and lower shoulders. Fig. 4 is a detail sectional view illustrating the manner of holding the bolt retracted to permit the sashes to slide freely in either direction. Fig. 5 is a vertical sectional view showing a rounded bolt, having a blunt engaging end. Fig. 6 is a vertical sectional view illustrating another modification of the invention. Fig. 7 is a rear elevation of the same. Fig. 8 is a transverse sectional view of the casing of the device shown in Fig. 6. Fig. 9 is a detail perspective view of the casing shown in Fig. 1. Fig. 10 is a detail per-

spective view of the bolt shown in Fig. 1. Fig. 11 is a similar view of the bolt shown in Figs. 6 and 7. Fig. 12 is a perspective view showing the sash-fastener mounted on the upper edge of the lower sash of a window at the center thereof and engaging a slotted rack.

Like numerals of reference designate corresponding parts in all the figures of the drawings.

1 designates a casing provided at opposite sides with ears arranged in pairs and designed to be secured to one side of a sash, as illustrated in Fig. 1 of the accompanying drawings, but it may be located at the center of the upper edge of a lower sash, as shown in Fig. 12. The casing 1, which is open at the back, as clearly shown in Fig. 9 of the drawings, is provided with a longitudinal recess or cavity 2, terminating short of the ends of the casing, which is provided at its front with a rectangular opening 3 and at its outer end with a circular opening 4. The front or inner end receives the engaging portion of a bolt 5, and the casing is provided at the outer end with a narrow slot 6, forming an entrance to the circular opening. The entrance-slot 6 is adapted to receive a narrow portion 8 of the bolt 5, which is drawn backward sufficiently to permit its engaging end to be introduced into and removed from the front portion of the casing when the said narrow portion 8 is at the entrance-slot 6. This construction enables the parts of the device to be readily assembled and permits them to be cast with the lugs or projections hereinafter described, and it greatly reduces the cost of construction, as the bolt and the casing do not require the drilling which is necessary when the knob and projection of the bolt are constructed separate and when the casing is not open for assembling the parts. The shank or body portion of the bolt is round to enable it to turn in the circular opening 4, and the narrow portion 8, which is formed by reducing the bolt at opposite sides, performs a double function, as it not only enables the bolt to be assembled, as heretofore described, but it also permits the spring to be readily arranged on the same. The narrow portion of the bolt is adapted to be placed between the end coils of a spiral spring 10, which may

then be screwed onto the bolt by simply rotating it.

The outer end of the bolt is provided with a suitable knob 11, which is cast integral with the same, and the front end thereof is provided with a squared portion 12 and a reduced outer engaging portion 13, which is beveled. The squared portion 12 fits snugly within the outer rectangular opening 3 of the casing, and when the bolt is retracted sufficiently to withdraw the squared portion 12 from such opening the bolt may be rotated a quarter of a revolution to arrange the beveled face at the top or at the side, as illustrated in Figs. 2 and 3 of the accompanying drawings. When the beveled face of the outer engaging portion of the bolt is uppermost, the lower sash is adapted to be raised freely and the upper sash may be lowered, and in windows not having sash-weights or other balancing devices this arrangement of the bolt will support the lower sash in an elevated position. When the beveled face of the bolt is arranged at one side, the bolt presents upper and lower shoulders, which lock the sashes against movement on each other. This arrangement will permit the upper and lower sashes of a window having sash-weights to be arranged for ventilating purposes, and it will lock the sashes against any further opening movement. The sashes may be arranged with a space at the top and bottom of the window for ventilation and a device for locking them together, so that while the sashes may have a slight bodily movement together they cannot be moved independently of each other.

The bolt is provided at the inner end of the rectangular portion 12 with a lug 13^a, arranged when the bolt is rotated to engage the opposite walls of the casing, whereby the bolt is prevented from rotating more than a quarter of a revolution. By rotating the bolt an eighth of a revolution the corners of the squared portions 12 are carried out of alignment with the corners of the rectangular opening and the bolt will be held out of engagement with the ratchet bar or strip 14.

The spring fits snugly around the body portion of the bolt, and in order to relieve it of strain the casing is provided at opposite sides with lugs 15, extending inward toward the bolt and adapted to be engaged by the head thereof to limit the inward movement of the same and to prevent too great a compression of the spring.

The ratchet-bar or rack 14, which consists of a strip of suitable metal, is provided with rectangular bends forming horizontal upper and lower shoulders adapted to be engaged by the bolt. The bolt may be engaged with the said shoulders, or a rack 15, which is provided with square openings 16, may be used, as shown in Fig. 12.

In Fig. 5 of the accompanying drawings the bolt is shown with a blunt engaging end 17, but the casing is constructed similar to that

heretofore described. This bolt is adapted to engage either form of rack or ratchet-strip and by rotating it an eighth of a revolution it may be held out of engagement to permit a sash to move freely in either direction.

In Fig. 6 of the accompanying drawings is illustrated another modification of the invention, in which the casing is provided adjacent to its inner end with parallel walls 19, forming guides for a narrow rectangular portion 20 of a bolt 21. The bolt 21 is adapted to operate similar to the bolt shown in Fig. 1 of the drawings, and when it is desired to rotate it the rectangular enlargement 20 is drawn backward opposite a groove 22, formed in the walls of the casing. The groove is sufficiently large to permit the bolt to be partially rotated, and this rotation is limited by a lug 23, similar to that heretofore described. The bolt is rounded in advance of the rectangular portion 20 and has a reduced engaging end 24, which is beveled. The body of the bolt is provided with a narrow portion 26, and the casing is provided at its outer end with an entrance-slot, and it has stops or lugs 27 to limit the movement of the bolt for preventing too great a compression of the spring.

The invention has the following advantages: The sash-fastener, which is simple and comparatively inexpensive in construction, possesses great strength and durability, and is adapted to be readily applied to any ordinary window. The bolt, which has a beveled edge or face at its engaging end, is adapted to be partially rotated to present either square shoulders or the bevel face to a rack or ratchet-strip, and it is capable of being arranged out of such engagement. The parts are adapted to be readily assembled and may be cast complete and do not require the drilling which is necessary with bolts having removable heads and projections. The narrow portion of the body of the bolt, which is adapted to be introduced into and removed from the casing through the entrance-slot, also permits the coiled spring to be readily placed on it.

Changes in the form, proportion, size, and the minor details of construction within the scope of the appended claims may be resorted to without departing from the spirit or sacrificing any of the advantages of this invention.

What is claimed is—

1. A device of the class described comprising a casing open at the back to form a recess and having openings at its ends communicating with the recess, one end of the casing being provided with an entrance-slot, and a bolt having an engaging portion at one end and a knob or handle at the other and provided between its ends with a reduced or narrow portion of a size to pass through the entrance-slot, substantially as described.

2. A device of the class described comprising a casing, open at its back to form a recess and provided at its ends with openings, said casing having an entrance-slot at one end com-

communicating with the adjacent opening, a reciprocating bolt provided at one end with an engaging portion having a knob at the other and provided between its ends with a reduced portion of a size to pass through the said entrance-slot, and a spring arranged on the bolt and adapted to be introduced on the same at the narrow portion thereof, substantially as and for the purpose described.

10. 3. A device of the class described comprising a casing open at its back to form a recess and provided at its ends with openings, and having an entrance-slot, said casing being provided at its inner end with a guiding portion 15 and being enlarged in rear of the same, and a bolt having a narrow portion to pass through the entrance-slot and provided with an enlargement fitting in the guiding portion of the casing and adapted to be drawn backward opposite the enlarged portion of the casing, whereby it may be partially rotated, substantially as described.

4. A device of the class described comprising a casing open at the back and provided 25 at its ends with openings and having an entrance-slot, a bolt provided with a narrow portion of a size to pass through the entrance-slot and having its engaging portion guided on the casing and adapted when drawn inward to be rotated, a lug carried by the bolt and arranged to engage the walls of the cas-

ing to limit the rotation, and a spring for actuating the bolt, substantially as described.

5. A device of the class described comprising a casing open at the back and provided 35 at its front with a rectangular opening and having an entrance-slot at the back, a bolt having a narrow or reduced portion to pass through the entrance-slot and provided with a polygonal portion guided in the said opening, said bolt being adapted to be retracted to withdraw its polygonal portion from the rectangular opening, and a lug carried by the bolt to limit its rotation, substantially as described.

6. A device of the class described comprising a casing open at the back and provided at its ends with openings, and having an entrance-slot, a bolt sliding in the casing and having a reduced portion to pass through the 50 slot, a spring arranged on the bolt, and a stop arranged on the casing and adapted to be engaged by the bolt to prevent the spring from being compressed too far, substantially as described.

In testimony that I claim the foregoing as my own I have hereto affixed my signature in the presence of two witnesses.

WILL S. JAMES.
